(57) **CLAIM**

The ornamental design for the socket tool, as shown and described.

DESCRIPTION

FIG. 1 is a front elevational view of the socket tool showing my new design;

FIG. 2 is a rear elevational view thereof;

FIG. 3 is a right side elevational view thereof, the left side elevational view being identical;

FIG. 4 is a top plan view thereof;

FIG. 5 is a bottom plan view thereof; and,

FIG. 6 is a perspective view taken from above and to the left. The socket receptacle in the top surface bottoms on a flat recessed surface, but no claim is made to any particular depth of the bottom surface below the top surface.

The broken line showing of the interior depth in FIG. 1 is for illustrative purposes only and forms no part of the claimed design.
